UNITED STATES PATENT OFFICE.

GEORGE H. LOTSPIKE, OF ROCHESTER, NEW YORK.

IGNITER.

SPECIFICATION forming part of Letters Patent No. 723,472, dated March 24, 1903.

Application filed June 18, 1902. Serial No. 112,168. (No model.)

To all whom it may concern:

Be it known that I, GEORGE H. LOTSPIKE, a citizen of the United States, residing at Rochester, in the county of Monroe and State of New York, have invented a new and useful Igniter, of which the following is a specification.

This invention is an improved construction of igniter or fire-lighter, the object being to provide a simple and efficient construction of device by means of which a fire can be quickly and easily started by simply pulling a cord or wire leading from the fire pot or chamber to the exterior of the stove or furnace.

With this object in view the invention consists, essentially, in the employment of a receptacle adapted to contain a combustible fluid and a cartridge or igniter adapted to be exploded or lighted immediately after releasing the contents of the receptacle.

The invention consists also in the novel construction of the cartridge or igniter and also in certain details of construction hereinafter fully described, and pointed out in the claims.

In the drawings forming a part of this specification, Figure 1 is a view illustrating the various parts of my invention. Fig. 2 is a sectional perspective view of the cartridge or igniter proper. Fig. 3 is an end view of the same. Fig. 4 is a longitudinal sectional view on the line 4 4 of Fig. 3. Fig. 5 is a transverse section on the line 5 5 of Fig. 4. Fig. 6 is a detail perspective view of the slide-wedge. Fig. 7 is a perspective view showing a slightly-modified construction.

In the proper embodiment of my invention I employ a receptacle A, which may be of any suitable size and material and is provided with a plug A', adapted to close the end, said receptacle being intended to receive and hold a liquid fuel, such as coal-oil, gasoline, or the like. A cord or wire B is fastened to one end of the receptacle A, and another cord or wire C is fastened to the plug A'. An elongated box or case D contains four longitudinal compartments or chambers E, which are filled with any suitable rapidly-combustible material F, and in practice I prefer to arrange these compartments or chambers E adjacent to the sides of a case D, leaving the central portion clear for the exploding cartridge or match G, which is preferably wedge-shaped

and is arranged between two wedge-shaped strips G', secured, respectively, to the top and bottom of the case D. The movable wedge or match G is coated with a suitable composition which will explode or ignite as soon as friction is applied thereto, and wedge-strips G' have their faces coated with similar material, so that when the movable wedge G is pulled out the match will be lighted, thereby igniting the combustible material contained within the chambers or compartments arranged within the case. The igniter after being lighted will burn for a short time and in so doing will thoroughly ignite the fuel, which has previously been covered by the light hydrocarbon released from the receptacle A, and in this manner the fire will be lighted, thus avoiding all the disagreeable features incidental to building a fire as ordinarily accomplished.

In order to provide for drawing out the wedge-shaped strip, I attach a wire or cord H thereto, said cord being also connected to the wire or cord B, and the opposite end of the cord H' is connected to the case D and also to the wire or cord C, adjacent to the plug A', so that when the wires or cords B and C are pulled for the purpose of releasing the liquid fuel from the receptacle A the wedge-shaped strip will be drawn from the case immediately afterward, thereby lighting the match and igniting the composition contained within the case. In order to prevent accidental lighting or exploding, I arrange a cushion I, of paper or other suitable material, at the end of each wedge-shaped strip, said cushions preventing the coated faces of the wedge-shaped strips contacting with each other until the wedge-shaped strip has been partly drawn out of the case.

In Fig. 6 I have shown the preferred manner of securing the wire or string to the match G, which consists in attaching the said wire or string to the sides at points G² and G³, and in Fig. 7 I have shown another method, which consists in boring a transverse hole G⁴, through which the wire or string can be passed.

It will thus be seen that I provide an exceedingly cheap and simple construction of fire lighter or igniter, one which can be arranged in connection with any construction

of stove or grate, and it will also be understood that the igniter proper or explosive cartridge can be used either with or without the receptacle containing the hydrocarbon fluid.

5 It should be stated that in practice the cord or chain C, which holds the plug A', is usually fastened at the farther end of the firebox or grate, which holds the plug stationary and allows the receptacle A to be pulled there-
10 from when the cord B is drawn upon.

Having thus fully described my invention, what I claim as new, and desire to secure by Letters Patent of the United States, is—

15 1. In a device of the kind described, a case having a compartment filled with a combustible composition, and a movable igniting-strip adapted to be lighted when moved within the case and set fire to the combustible material contained within the compartment,
20 substantially as specified.

25 2. In a device of the kind described, a case having compartments arranged therein and adapted to contain combustible or explosive material, stationary strips arranged within the case, and a movable strip arranged between the stationary strips, the contiguous faces of the said strips being coated with an ignitable composition capable of being ignited by friction, together with means for moving
30 the said movable strip for the purpose of igniting the composition as specified.

3. The combination with a receptacle having a plug and adapted to contain a liquid fuel, an igniter having a central friction igniting strip or match, and one or more compartments containing combustible composition with means for removing the plug from the receptacle and operating the igniting-match, substantially as set forth. 35

4. The combination with a receptacle having a plug of the wires or cords connected to the receptacle and plug, the case having compartments filled with combustible material the stationary strips and the movable strip, the contiguous faces of said strips being coated with an ignitable material, and the wires or cords connected to the strip and also to the case for the purpose specified. 40

5. In a device of the kind described, the combination with a case having compartments filled with combustible material, the stationary strips, and the movable strip, the contiguous faces of said strips being coated with ignitable material, means for moving the said movable strip, and the cushion-pieces 50 connected to the ends of the fixed and movable strips for the purpose specified. 55
